US0D1098200S

(12) **United States Design Patent** (10) **Patent No.:** **US D1,098,200 S**
(45) **Date of Patent:** **** Oct. 14, 2025**

(54) **COOLANT EXPANSION TANK**

(71) Applicant: **Resource Intl Inc.**, New Castle, DE (US)

(72) Inventor: **David Zdichowski**, Wilmington, DE (US)

(73) Assignee: **Resource Intl Inc.**, New Castle, DE (US)

(**) Term: **15 Years**

(21) Appl. No.: **29/895,536**

(22) Filed: **Jun. 22, 2023**

(51) **LOC (15) Cl.** **15-01**

(52) **U.S. Cl.**

USPC **D15/5**; D23/202

(58) **Field of Classification Search**

USPC D15/5; D12/166, 218; D23/202, 313, D23/324; D9/682

(57) **CLAIM**

The ornamental design for a coolant expansion tank as shown and described.

DESCRIPTION

FIG. 1 is a top front perspective view of the coolant expansion tank according to the present application;

FIG. 2 is a top rear perspective view of FIG. 1;

FIG. 3 is a side view of FIG. 1;

FIG. 4 is a side view of FIG. 1;

FIG. 5 is a front view of FIG. 1;

FIG. 6 is a rear view of FIG. 1;

FIG. 7 is a top view of FIG. 1; and,

FIG. 8 is a bottom view of FIG. 1.

The broken line showing is included for the purpose of illustrating unclaimed subject matter and forms no part of the claimed design.

The shade line showing is included for the purpose of illustrating contour and not surface ornamentation.

1 Claim, 8 Drawing Sheets
